Primary Examiner — Marissa J Cash*Assistant Examiner* — Altaira J Swangin(57) **CLAIM**

The ornamental design for a “computer,” as shown and described.

DESCRIPTION

FIG. 1 is a top front right perspective view of a computer showing my new design;

FIG. 2 is a bottom rear left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines illustrate portions of the computer and form no part of the claimed design.

1 Claim, 8 Drawing Sheets(56)
